UNITED STATES PATENT OFFICE.

WILLIAM HEBDON, OF NEW BRIGHTON, ASSIGNOR TO THE AMERICAN CLOTH WORKERS COMPANY, OF NEW YORK, N. Y.

METHOD OF AND MACHINE FOR SHRINKING, DRYING, AND FINISHING CLOTH.

SPECIFICATION forming part of Letters Patent No. 276,036, dated April 17, 1883.

Application filed May 24, 1882. (No model.)

To all whom it may concern:

Be it known that I, WM. HEBDON, of New Brighton, in the State of New York, have invented an Improved Method of and Machine 5 for Shrinking, Drying, and Finishing Cloth, of which the following is a specification.

The object of my invention is to dampen and shrink cloths and other fabrics in such a way that the operation will be uniform and rapid, 10 then to dry and finish, as hereinafter described.

Figure 1 of the drawings is a sectional view on line *y y* of Fig. 2, illustrative of my apparatus. Fig. 2 is a plan view of the same. Fig. 15 3 is a side elevation of the drier and the means for drawing the cloth through it. Fig. 4 is a sectional plan view on line *x x* of Fig. 3.

A represents the water-tank; *a a*, two rolls near the bottom thereof; *b*, two pairs of squeezing-rolls arranged over the tank, and a little 20 farther apart than the rolls *a a*. The rolls *a a* are journaled in the sides of the tank and the rolls *b* in a supporting-frame above the tank. In this frame are also journaled the rolls *c c*, from the latter of which, as shown in Fig. 1 of 25 the drawings, the damping-sheet passes between the front pair of squeezing-rolls *b b* down into the tank, around the rolls *a a*, up to and between the second pair of squeezing-rolls and to the roll *c*. At the ends of said supporting-frame are journaled the friction-rolls *d d'*, the 30 one next to the drier not being used when the drier is at that end.

B represents the drier-frame, which may be connected by a hook and eye or other detachable connection with either end of the roller-supporting frame on the tank, so that either roll *c* or *e* will be the winding and the other the unwinding roll, as the drier may be connected with one or the other side of the roller-supporting frame. Thus it will be perceived 40 that one of the rolls *c e* serves to discharge one piece of cloth while the other is receiving a second piece.

In the drier-frame *B* is arranged the tube *f*, 45 which is supplied with steam by a pipe, *h*, connected by a flexible tube with the steam-space of a boiler, the tube *f* being bent to form spaces for the reception of the rolls *i i*, which are journaled in the frame *B*, and around which 50 the cloth passes, and being provided at the

lowest points of its bends with the pipes *g* to allow the water of condensation to escape. Over each end of the tube *f* is arranged a finishing or pressing roller, *k*, the one next to the tank being made to press the cloth as it comes 55 from the roll *e*, as shown in Fig. 1 of the drawings, and both being pressed down on the cloth by springs, which act upon their bearings. Over each upward convexity of the tube *f* are arranged the friction-rolls *l*, which press 60 the cloth to the tube.

D is a frame carrying the roll *m*, which may be operated by a hand-crank to draw the cloth from the roll *e*, as shown in Figs. 1 and 3 of the drawings, through the drying-frame and 65 to wind up the same.

In Fig. 3 of the drawings, *a'* represents four double pulleys and *a²* belts for connecting the said pulleys with the pulley *m*, the belts being so arranged as to rotate the rollers *i i* in the 70 same direction, to assist the forward movement of the cloth which is being drawn through the drying-frame.

The operation by which I shrink, dry, and finish the cloth is as follows: As shown in Fig. 75 1 of the drawings, the cloth passes from the bolt to the roller *c*, on which it is to be wound with the dampening-sheet, is then carried over the friction-roll *d*, around the bolt-board, and up again over the friction-roll *d* to the 80 roll *c*, the bolt being thus hung or supported in a bag or loop of the cloth. The dampening-sheet is wound on roll *c* at the same time with the cloth, and the roll *c*, as well as the roll *e*, is provided with a hand-crank on its 85 shaft. After the dampening-sheet has been drawn through the water and wrapped about the fabric the outer end, which has last come from the cloth-board, is carried through the drier. Here it is first passed under roll *k*, then 90 under rolls *i i*, and then under the second roll *k* to the drawing-roll *m*, being thus drawn through the drying-frame in close proximity to the steam-heated tube *f*, which is provided with the spring-valve *n* and air-inlet valve *o*, 95 as shown in Fig. 4 of the drawings, to regulate the steam-pressure and admit air when the steam is cut off. As the cloth is dampened when of a single thickness and spread to its full width, the shrinking is uniform, while the 100

drawing of it through the frame of the drier by the hand-operated roll *m* on the frame *D* enables it to be completely dried and perfectly finished. The drawing-frame *D* is now disconnected from the drying-frame and the latter from the roller-supporting frame, so that each may be separately moved around to the other end of the roller-supporting frame, where they may be again connected with said roller-supporting frame and with each other. That one of the rollers *c e* which was before the winding-roll now becomes the unwinding-roll, and the one which was the unwinding-roll now becomes the winding-roll.

15 The tank is provided with a central superposed roll, *o*, for shrinking canvas, duck, and linens which require to be saturated. This may be done without interfering with the ordinary dampening operation, the material being wound directly from the tank to the roll and there left for the water to drain off from it. After remaining over night I usually run the canvas, duck, or linen through the drier and on the roller *m* before commencing to

25 dampen cloth.

p represents rollers over which the canvas is carried when too wet for contact with the tube *f*. Then it passes around rollers *i i* and out to the winding-roll *m*. It is sometimes advisable to pass it a second time through the drier. The dampening-sheet *r* is connected at its ends to the rolls *c e* and passes back and forth from one to the other, but sometimes requires to be separated from one roll and passed

35 through the drier to prevent it from becoming mildewed.

The advantages of my invention consist in the continuity and rapidity of its operations, the uniformity in the dampening and shrinking, and in the thoroughness with which the cloth is dried and finished. It is also to be observed that the dampening, shrinking, drying, and finishing may all be carried on at the same time, while the nap may be laid and a beautiful finish given to faced goods by passing them fag end foremost over the heated metallic surfaces; also, that the middle crease in the cloth is removed, so that in doubling it for cutting the selvages may be placed edge to edge and the cloth cut to the best possible advantage.

What I claim as new and of my invention is—

1. A method of shrinking, drying, and finishing cloth and similar fabrics, which consists in first rolling a single thickness of material in a dampening-sheet, then passing it over a heated surface, and finally pressing it, as described.

2. The combination of the rolls *a b*, end roll, *d*, and rolls *c e*, to allow the cloth and dampening-sheet to be simultaneously wound in alternate layers about the roll *c*, as described.

3. The combination, with the roll *e*, of the rolls *i k l*, the tube *f*, and the roll *m*, to enable the cloth to be drawn from said roll over a heating-surface, as described.

WILLIAM HEBDON.
